US0D1070077S

(12) **United States Design Patent** (10) **Patent No.:** **US D1,070,077 S**
(45) **Date of Patent:** **** Apr. 8, 2025**

(54) **ABSORBENT ARTICLE**

(71) Applicant: **The Procter & Gamble Company**,
Cincinnati, OH (US)

(72) Inventor: **Tara M. Hale**, Cincinnati, OH (US)

(73) Assignee: **The Procter & Gamble Company**,
Cincinnati, OH (US)

(**) Term: **15 Years**

(21) Appl. No.: **29/945,020**

(22) Filed: **May 31, 2024**

Related U.S. Application Data

(60) Continuation of application No. 29/915,871, filed on Nov. 6, 2023, now Pat. No. Des. 1,036,657, which is a division of application No. 29/847,536, filed on Jul. 26, 2022, now Pat. No. Des. 1,010,814, which is a division of application No. 29/765,271, filed on Jan. 7, 2021, now Pat. No. Des. 962,426.

(57) **CLAIM**

The ornamental design for an absorbent article as shown and described.

DESCRIPTION

FIG. 1 is a perspective view of another absorbent article showing the front and right sides of the absorbent article; FIG. 2 is a view of the front side of the absorbent article of FIG. 1;

FIG. 3 is a view of the right side of the absorbent article of FIG. 1;

FIG. 4 is a view of the back side of the absorbent article of FIG. 1;

FIG. 5 is a view of the left side of the absorbent article of FIG. 1;

FIG. 6 is a view of the top side of the absorbent article of FIG. 1; and,

FIG. 7 is a view of the bottom side of the absorbent article of FIG. 1.

The broken lines shown in FIGS. 1-7 illustrate portions of the absorbent article that form no part of the claimed design. Any patent applications or patents to which this application claims benefit thereof under 35 U.S.C. § 119(e), 120, or 121, are hereby incorporated herein by reference in its entirety.
